LOOM REED

Edgar R. Bond and Clarence A. Hobbs, Greensboro, N. C., assignors to Textile Specialty Company, Greensboro, N. C., a corporation of North Carolina

Original application January 29, 1937, Serial No. 122,896. Divided and this application October 27, 1938, Serial No. 237,282

4 Claims. (Cl. 139—192)

This invention relates to an improved type of loom reed of the pitch band type and is a divisional application taken from our co-pending application for patent, Serial No. 122,896, filed 5 January 29, 1937, Pat. No. 2,149,204 of February 28, 1939.

The primary object of this invention is to provide a loom reed so that the finished rib will gauge correctly as to diameter at all points 10 thereon. Heretofore, in the manufacture of cotton reeds of the pitch band type, it has not been possible to get an accurate gauge of the ribs for the entire length. This irregularity of the diameter is caused partially from the half round 15 wood strips which are used on each side of the splits and clamped therearound by a pitched twine. These wood strips are subject to a varied amount of shrinkage, since they do not have a uniform degree of hardness. Also the tension 20 on the pitched twine will grow greater as the diameter of the spool from which it is drawn grows smaller, during the formation of the reed, resulting in a tighter winding of the pitched yarn as the spool becomes empty. All of this variation 25 in the gauge of the ribs of the reeds causes much trouble in cotton weaving. For example, a loom may be aligned to take a certain reed, and upon turning this reed end for end, or turning the reed upside down, the inaccuracy of the rib 30 will necessitate the realigning of the loom, because the ribs are not accurate and thus are not properly centered. Should the loom not be aligned, every time the reed is installed, the loom 35 will not operate smoothly and the wear on the shuttle will be excessive.

It is a further object of this invention to provide a loom reed having the rib thereof encased in a metallic sheet or band of uniform diameter, this band being adhesively secured around the 40 rib of the reed, and also having the ends thereof projecting past the ends of the rib and crimped over the ends thereof to additionally secure the band on the rib.

Some of the objects of this invention having 45 been stated, other objects will appear as the description proceeds when taken in connection with the accompanying drawing, in which—

Figure 1 is an elevation of a portion of a loom reed of the pitch band type showing a 50 metallic casing enclosing a portion of the ribs and broken away from other portions thereof;

Figure 2 is a sectional view through one of the ribs and taken along the line 2—2 in Figure 1;

Figure 3 is a sectional plan view taken along 55 the line 3—3 in Figure 1;

Figure 4 is an isometric view of the left-hand end of Figure 1;

Figure 5 is an isometric view of a portion of a comb with our covering thereon.

Referring more specifically to the drawing, 5 the numeral 10 denotes a suitable loom reed made in accordance with the invention. This reed has end bars 11 and splits 12, the ends of which are clamped between semi-circular, or half round members 14. The splits are spaced 10 apart from each other by means of a pitched cord 15 which is spirally wound around both of the members 14 during the construction of the reed. Additional metallic strips such as indicated by the reference character 16 are provided 15 to re-enforce the half-round members 14. These metallic members 16 are likewise bound in the half-round members by means of the spiraled pitched cord 15. After the cord 15 has been wound around both of the half round members, 20 a suitable cuff 18 is secured on each end thereof by means of suitable nails 19. This cuff also serves to hold the end bars 11 in position.

With the reed formed to this point, a suitable metallic band 20 is formed over each rib so 25 that the finished rib will be symmetrical at all points about the vertical center line of the splits. This band has a suitable adhesive 21 applied to one side thereof, so that the projecting ends of splits 12 will be properly secured to the metal- 30 lic band 20.

By providing the adhesive material 21, which is usually of pitch, tar, or some other suitable adhesive substance, the vacant spaces between the ends of the projecting splits are properly 35 filled. Also the pitch 21 on the interior surface of the metallic band 20 mixes with the pitch on the exterior of the spiraled cord 15. It is thus seen that the splits are securely anchored between the half round members, thus eliminating 40 any necessity of bending the projecting ends to secure them in position.

It will be noted by observing Figure 4 that each end of the metallic casing 20 is crimped as at 45 22, so that the ends of ribs will have a neat appearance. The crimped end also serves as an additional means for securing the metallic band properly upon the half round members.

Figure 5 is an isometric view of a portion of a comb 25 having its rib covered identically in 50 the same manner as the ribs of the loom reed 10 are covered. This comb has end bars 11' and splits 12' which are clamped between half-round wood members 14' and which are spaced apart from each other by spiraled cord 15' substan- 55

tially as in the preceding case. This rib also has metallic bars 16', cuffs 18' and nails 19'. A cover 20' is folded around the rib and crimped over the ends thereof as at 22' thereby providing 5 a comb whose rib will gauge correctly, as to diameter at all points.

In the drawing and specification there has been set forth a preferred embodiment of the invention and although specific terms are employed they are used in a generic and descriptive sense only and not for the purposes of limitation, the scope of the invention being set forth in the appended claims.

We claim:

- 15 1. A loom reed, comb and the like formed from splits held in spaced relation to each other by a half-round wooden member on each side of the splits near each end thereof, and having a pitched cord wound spirally around the half-round members and passing between the splits to space the same from each other, a metallic covering for the half-round members completely encasing the half-round members and the outer ends of the splits, the ends of the metallic covering being crimped inwardly over and against the ends of the half-round members.
- 20 2. A loom reed, comb and the like formed from splits held in spaced relation to each other by a half-round wooden member on each side of the splits near each end thereof, and having a pitched cord wound spirally around the half-round members and passing between the splits to space the same from each other, a metallic covering for the half-round members completely
- 25

encasing the half-round members and the outer ends of the splits, the ends of the metallic covering being crimped inwardly over and against the ends of the half-round members, and an adhesive disposed between the ends of the splits and adhering to the interior surface of the metallic covering.

3. A cotton loom reed, comb and the like having a rib formed from a pair of half-round members engaging opposed edges of the splits forming a part of the reed, comb and the like, a unitary metallic covering for the rib completely covering the half round members and the outer ends of the splits and having its edges in close proximity to an intermediate portion of the splits, the ends of the covering being restricted by having their edges crimped inwardly against the ends of the rib to securely position the covering on the rib.

4. A cotton loom reed, comb and the like having a rib formed from a pair of half-round members engaging opposed edges of the splits forming a part of the reed, comb and the like, a metallic covering for the rib completely covering the half round members and the outer ends of the splits and having its edges in close proximity to an intermediate portion of the splits, the ends of the covering being restricted by having their ends crimped inwardly against the ends of the rib to securely position the covering of the rib, and an adhesive disposed between the ends of the splits and the covering.
